UNITED STATES PATENT OFFICE.

IKUNOSUKE MORI, OF LOS ANGELES, CALIFORNIA.

MANUALLY-OPERATED POWER-BOAT.

1,244,068.

Specification of Letters Patent. Patented Oct. 23, 1917.

Application filed April 2, 1917. Serial No. 159,332.

To all whom it may concern:

Be it known that I, IKUNOSUKE MORI, a subject of the Emperor of Japan, residing at Los Angeles, in the county of Los Angeles and State of California, have invented 5 certain new and useful Improvements in Manually-Operated Power-Boats; and I do hereby declare the following to be a full, clear, and exact description of the invention, 10 such as will enable others skilled in the art to which it appertains to make and use the same, reference being had to the accompanying drawings, and to the letters and figures of reference marked thereon, which form a 15 part of this specification.

This invention relates to new and useful improvements in manually-operated boats and comprises a simple and efficient device of this nature having various details of construction, combinations and arrangements 20 of parts which will be hereinafter fully described, shown in the accompanying drawings and then specifically defined in the appended claims.

25 I illustrate my invention in the accompanying drawings which, with the letters of reference marked thereon, form a part of this specification and in which:—

Figure 1 is a side elevation of my invention.

Fig. 2 is a rear elevation.

Fig. 3 is a sectional view on line 3—3 of Fig. 1, and

Fig. 4 is a top plan view.

35 Reference now being had to the details of the drawings by letter, A designates the hull of a boat having a steering rudder B at one end, and C, C are levers pivoted at C', one upon each side of the boat, and have connections through the rod C² and the chain 40 C³ with the rudder. Securely fastened to the bottom of the boat and projecting downwardly therefrom are the hangers D and E, to the lower ends of which the parallel and 45 horizontally disposed bars H are secured and spaced apart by means of the pipe sections I through which bolts J pass upon which nuts J' are mounted.

50 Mounted in suitable bearings in a downwardly projecting portion of the bar H is a shaft L to which the propelling wheels L' are fixed, said shaft having keyed thereto a gear wheel L². A second shaft N is also journaled in a suitable bearing on one of the 55 bars H and has journaled thereon a master

gear wheel O, the teeth of which mesh with those of the gear wheel L² and upon said wheel O is a crank pin Q to which one end of the pitman R is pivoted.

An oscillating operating member 60 comprises two bars M and M' which are fastened together and their lower portions are outwardly curved as at M² and the lower ends of said bars are pivotally mounted upon one of the bolts J. Handles M³ are connected to 65 the upper ends of said bars M and M'. A pivotal pin P is carried by the bars M and M' and between which one end of the pitman R is pivoted. Said bars are mounted in an elongated slot T formed in the bottom 70 of the boat, said slot having a suitable wall T' about the same to prevent water passing through the slot into the boat.

By the provision of an apparatus embodying the features of my invention, it will 75 be noted that the operative mechanism of the apparatus is secured underneath the boat, the only portion projecting up through the hull being the oscillating lever having the handles whereby the operator, by sitting 80 in the boat, may, through the gear mechanism shown, impart an accelerated movement to the propellers by the swinging of the lever backward and forward.

What I claim to be new is:—

85 1. A hand power propelled boat comprising a hull, hangers secured to the bottom of the boat, bars secured to said hangers, a propeller shaft journaled in suitable bearings upon said bars, an oscillating lever projecting through the boat, and handles thereon, and pivotal pitman and gear connections between said lever and propeller.

90 2. A hand power propelled boat comprising a hull, hangers secured to the bottom of the boat, bars secured to said hangers, a propeller shaft journaled in said bars, a gear wheel and a propeller fixed to said shaft, a master gear wheel meshing with the gear wheel upon the propeller shaft, an oscillating lever, a pitman having pivotal connection between said master gear wheel and lever.

95 3. A hand power propelled boat comprising a hull, hangers secured to the bottom of the boat, bars secured to the lower portions of said hangers and spaced apart, a propelling shaft journaled in downwardly projecting portions of said bars, propellers fixed to said shaft, a gear wheel fixed to the latter, 100

110

a master gear wheel journaled between said bars and in mesh with the gear wheel upon the propelling shaft, a pivotal pin supported by said bars, an oscillating lever pivotally mounted upon said pin, and pitman connections between said lever and master gear wheel.

Copies of this patent may be obtained for five cents each, by addressing the "Commissioner of Patents, Washington, D. C."

In testimony whereof I hereunto affix my signature in presence of two witnesses.

IKUNOSUKE MORI.
